(57) **CLAIM**

We claim the ornamental design for an oven range, as shown and described.

DESCRIPTION

FIG. 1 is a top, front and right-side perspective view of an oven range showing our new design;

FIG. 2 is a bottom, front and right-side perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a top, front and right-side perspective view of the oven range showing a state of the upper control panel opened;

FIG. 10 is a bottom, front and right-side perspective view thereof;

FIG. 11 is a front elevation view thereof;

FIG. 12 is a rear elevation view thereof;

FIG. 13 is a left-side elevation view thereof;

FIG. 14 is a right-side elevation view thereof;

FIG. 15 is a top plan view thereof;

FIG. 16 is a bottom plan view thereof; and,

FIG. 17 is a top, front and right-side perspective view showing a state of the water tank thereof being pulled-out. The broken lines depict portions of the oven range that form no part of the claimed design. The dot-dash lines in FIG. 17 indicate a position where the water tank thereof is pulled out.
